UNITED STATES PATENT OFFICE.

ELMER E. F. CREIGHTON, OF SCHENECTADY, NEW YORK, ASSIGNOR TO GENERAL ELECTRIC COMPANY, A CORPORATION OF NEW YORK.

PROTECTIVE DEVICE.

Application filed March 19, 1924. Serial No. 700,419.

To all whom it may concern:

Be it known that I, ELMER E. F. CREIGHTON, a citizen of the United States, residing at Schenectady, in the county of Schenectady, State of New York, have invented certain new and useful Improvements in Protective Devices, of which the following is a specification.

My invention relates to protective devices or systems, and has for its object the provision of an improved device of this character which is reliable in operation.

The fuse, which is one of the earliest devices used to protect electric circuits, is now manufactured in a variety of forms which have become more or less standard. Among them may be mentioned the expulsion fuse, the filled tube fuse, and the open air fuse. In its common forms, however, the fuse has the disadvantage that it is not entirely reliable in operation. This is due largely to the fact that a momentary overload may decrease the sectional area of the fusible element and thereby cause it to fail under normal operation conditions.

In the case of the expulsion fuse, it is common practice to make the container of strong fiber or the like because of the fact that non-carbonaceous materials, such as porcelain, have insufficient strength to withstand the pressure generated by vaporization of the fusible element. With this construction, the fiber container is apt to carbonize on its inner surfaces thereby forming a more or less conductive path in shunt to the fusible element. When this occurs the fuse cannot be relied upon to interrupt the circuit.

The filled tube fuse comprises a container in which is placed a fusible element surrounded by a filler such as pellets of plaster Paris and slaked lime. The effectiveness of this filler depends to a large extent on its moisture content which is utilized to absorb the heat of the metal vapor and to quench the arc which follows melting of the fusible element. This construction is objectionable in that a very heavy overload is required to vaporize the fusible element if its energy loss under normal conditions is made low enough to leave the moisture of the filler unaffected.

In accordance with my invention a plurality of fusible elements, such as wires

or thin strips of metal, normally in parallel relationship with each other are connected in series with the circuit to be protected and means responsive to excess current in the circuit are provided for changing the connection of these elements from parallel to series. Under these conditions the fusible elements are maintained cool under normal conditions but are suddenly melted or vaporized when the circuit is traversed by current of a predetermined higher value.

My invention will be better understood from the following description when considered in connection with the accompanying drawing, and its scope will be pointed out in the appended claims.

The single figure of the drawing schematically shows a plurality of fusible elements 1, 2, and 3 surrounded by insulating tubes 4, 5 and 6, which may contain a suitable filler if desired. These tubes may be supported in any convenient manner. The fusible element 1 is shown as connected between conducting members 7 and 8, the fuse 2 as connected between conducting members 7 and 9, and the fuse 3 as connected between conducting members 9 and 10. A contact member 11 controlled by the armature 12 of an electromagnet 13 is arranged to interconnect the members 7 and 10. A contact member 16 for interconnecting the members 8 and 9 is controlled by the armature 15 of the electromagnet 14. The armatures 12 and 15 are illustrated as provided with springs 17 and 18 respectively for biasing them to positions in which the contacts 11 and 16 are closed. The operating coils 19 and 20 of the electromagnets 13 and 14 are adapted to be interconnected with an electric circuit through leads 21 and 22 respectively.

It will be apparent that in the illustrated closed position of the contacts 11 and 16 the fuse wires 1, 2 and 3 are connected in parallel between the leads 21 and 22. When the contacts 11 and 16 are moved to their open position due to excessive current in the coils 19 and 20, however, fuse wires 1, 2 and 3 are connected in series between leads 22 and 21. Under these conditions the entire current traverses each wire and the energy consumed in heating the wires is suddenly increased in the ratio of 1

to 9. It is thus possible to operate the fuse wires at a low temperature under normal load conditions and to heat them suddenly to the point of melting or vaporization when the circuit is traversed by a current of predetermined value. Obviously the number of fuse wires may be made larger to increase the difference between the amount of energy consumed in heating them under normal load conditions and that likewise consumed when an overload occurs and the coils 19 and 20 are energized to move contacts 11 and 16 out of engagement with the cooperating stationary contacts.

This method of normally operating the fuses at a low temperature and suddenly increasing their temperature when an overload occurs has a number of advantages. Due to the sudden increase in the current carried by the various fusible elements it is feasible to make them of highly conductive, high melting point, metals such as copper or aluminum. The higher conductivity of these metals permits the use of a smaller mass of metal with a consequent reduction in the quantity of vapor required to be cooled. Also when a filler is used its moisture content is so briefly in contact with hot metal that it is practically unaffected until brought into action to extinguish the arc which follows the melting of the fuse.

The electromagnets 13 and 14 may be arranged to operate instantaneously in response to a predetermined value of current, or may be adapted to operate as definite or inverse time element relays.

While I have shown my invention diagrammatically for the purpose of explaining its principle and the preferred mode of its operation as required by the patent statutes, it will be apparent to those skilled in the art that it may be embodied in many other forms than that shown and described. No limitation is to be put on either the number of parallel fuse-blocks or the form of these fuse-blocks. The terms of the appended claims are, therefore, not limited to the precise structure disclosed but are intended to cover all changes and modifica-

tions within the spirit and scope of my invention.

What I claim as new and desire to secure by Letters Patent of the United States, is:—

1. A system of the class described comprising a plurality of fusible elements normally connected in parallel, relatively movable conductors for controlling the connections of said elements, and means for producing relative movement between said conductors to connect said elements in series with one another when they are traversed by current in excess of a predetermined value.

2. In a system for protecting an electric circuit, the combination of a plurality of fusible elements, a plurality of stationary conductors for connecting said elements in series with one another, a plurality of movable conductors for interconnecting said stationary conductors to connect said elements in parallel with one another, and current responsive means for moving said movable conductors out of contact with said stationary conductors when said elements are traversed by current in excess of a predetermined value.

3. A device of the class described comprising a plurality of fusible elements normally connected in parallel, and means for causing said elements to be connected in series with one another.

4. A device of the class described comprising a plurality of fusible elements normally connected in parallel, and means for causing said elements to be connected in series when they are traversed by current in excess of a predetermined value.

5. A protective system comprising a plurality of fusible elements normally connected in parallel, contact members for causing said elements to be connected in series, and electro-responsive means for operating said contact members when said elements are traversed by current in excess of a predetermined value.

In witness whereof, I have hereunto set my hand this 18th day of March 1924.

ELMER E. F. CREIGHTON.
